UNITED STATES PATENT OFFICE.

JESSE M. STANSELL AND CHARLES D. OLAND, OF CENTRALIA, ILLINOIS, ASSIGNEES TO
ELECTRO PNEUMATIC SKID COMPANY, OF CENTRALIA, ILLINOIS.

AUTOMATIC RAILWAY-SKID.

1,148,870.

Specification of Letters Patent.

Patented Aug. 3, 1915.

Application filed January 25, 1915. Serial No. 4,344.

To all whom it may concern:

Be it known that we, JESSE M. STANSELL and CHARLES D. OLAND, citizens of the United States, residing at Centralia, in the county of Marion, State of Illinois, have invented certain new and useful Improvements in Automatic Railway-Skids; and we do hereby declare the following to be a full, clear, and exact description of the invention, such as will enable others skilled in the art to which it appertains to make and use the same.

This invention relates to an automatic railway skid adapted to be employed in connection with a railway track for impeding and stopping the travel of a car along the track.

As is well known, at large railway centers the yards usually cover considerable area and are provided with numerous tracks and sidings. In order to facilitate the shifting of the cars and making up of trains of cars, a large railway yard usually has both a "receiving" yard and a "classification" yard, with a declivity or "hump" leading from the "receiving" yard to the "classification" yard. Thus the "receiving" yard is elevated above the "classification" yard, and into the "receiving" yard are brought cars which are intended for various destinations. For instance, at the "receiving" yard may be cars intended for half a dozen different cities, located in various parts of the country, and in order to classify or separate the cars so that all cars intended for one city will be brought together upon the same track, the "classification" yard is provided below the "receiving" yard, and as this "classification" yard is provided with a number of sidings or spur tracks leading off from the tracks running down the "hump" or declivity from the "receiving" yard, it is the practice to put an operator in charge of each car as it leaves the "receiving" yard for the "classification" yard. As a car travels by gravity down the "hump" or declivity, the operator in a switch tower throws the proper switch so as to cause the car to travel onto the selected auxiliary or branch track in the "classification" yard, it being understood that all cars intended for the same point of destination are run onto the same auxiliary track in such "classification" yard. The brakeman or trainman having charge of

the car passing down the "hump" or declivity to an intended track in the "classification" yard has charge of the braking mechanism of his car and is supposed to apply the brakes after the car reaches the intended spur track in the "classification" yard, and thereby stop the car at the proper point on such track. It frequently happens, however, that the braking mechanism fails to work, with the result that the momentum of the car carries it along the branch track beyond the intended point, and that disastrous collisions, with injury and loss of life and damage to property and equipment oftentimes occur.

The purpose of our invention, therefore, is to provide mechanism for stopping the car upon the track in the "classification" yard should the braking equipment of the car fail to work, and by so stopping the car the disastrous accidents, such as above mentioned, are avoided.

It is also our purpose to provide an automatic skid for stopping the car, which is normally out of operation at the branch track in the "classification" yard, but which may be thrown into operation by the switchman in the switch tower for the purpose of stopping the car when the switchman is notified by a signal from the brakeman on the traveling car that the braking equipment of his car will not work and that such car is "running away."

It is also our purpose to provide an automatic car stopping apparatus of the class mentioned which will embody the desired features of simplicity, efficiency, reliability and safety, and which may be manufactured and installed, operated and employed with a railway yard system at a relatively low cost.

With the above recited objects and others of a similar nature in view, our invention consists in the construction, combination and arrangement of parts set forth in and falling within the scope of the appended claims.

In the accompanying drawings: Figure 1 is a top plan view of a portion of a railway track having our invention applied thereto. Fig. 2 is a view in side elevation showing one position of our apparatus. Fig. 3 is a similar view showing the second position of the apparatus or when both skids have been brought into position on the

track to stop the travel of the car. Fig. 4 is an enlarged detail view of the sliding-skid and the trip lever operated thereby, looking from the inside of the track rail. Fig. 5 is a vertical cross sectional view taken on the line 5-5 of Fig. 2. Fig. 6 is a cross sectional view taken through the rail skid on the line 6-6 of Fig. 2. Fig. 7 is a detail perspective view of the rocking lever of the rail skid. Fig. 8 is a perspective view of one of the sliding skids or blocks. Fig. 9 is a vertical cross sectional view taken through the pneumatic device located in a pit alongside the trackway and adapted to operate the front skid. Fig. 10 is a similar view, but showing the parts of the pneumatic device in inoperative position, that is to say, with the air cut off therefrom. Fig. 11 is a cross sectional view taken on the line 11-11 of Fig. 9. Fig. 12 is a similar view taken on the line 12-12 of Fig. 10.

Referring now to the accompanying drawings in detail, the letter A designates one of the rails of a railway track while the ties 25 are shown at B. A car on the trackway is conventionally shown at C with the front wheeled truck indicated at D and the rear wheeled truck at D'. Spaced wells or pits E and E' are located alongside the trackway, the distance between the two pits being substantially or approximately equal to the distance between the rear wheels of the front truck and the front wheels of the rear truck. In the pit E is located the mechanism for pneumatically operating certain parts of the apparatus as will be hereinafter described.

The front skid of the apparatus is shown at F and is adapted to impede and chock the front truck D, while the rear skid is shown at F' and is adapted to impede and chock the rear truck of the car. These two skids are in the nature of blocks slideable on the rail A, and as the blocks are similar in construction a description of one will suffice. Referring to Fig. 8 of the drawings, it will be seen that each block comprises a head section 1 and a tail section 2. The bottom of the head is recessed as at 3, and in this recess is housed a transversely disposed roller 4. The top of the head is flattened as at 5, and this flattened top is provided with a transverse groove 6 which extends half way across the top. The tail 2 of the block has a flat bottom face 7 which is adapted to bear upon the rail, a beveled end 8, and a concaved top face 9 extending between the beveled end 8 and the flat top 5 of the head. The side wall 10 of the head which lies at the inside of the ball of the rail when the skid block is positioned thereon is spaced apart from the adjacent side of the tail of the block so that a segmental groove 11 is formed which is adapted 65 to accommodate the car wheel flange, and it

will be further noted that the sides of the head of the block extend below the bottom face 7 so as to form flanges which lie at the sides of the ball of the rail. The side wall 12 of the head, which lies at the outside of the rail is provided with an outwardly extending lug 13 for the purpose hereinafter mentioned.

The numeral 14 indicates a metallic guide rod which extends alongside the rail, but is 75 spaced apart from the outer face thereof, and each block or skid is provided with clamping clips 15 which are adapted to engage with the rod 14, and while these clips permit the skid to slide along the track they 80 also act as loose hinges so that the skid or block may be thrown from off the rail to a position at one side thereof as shown in Fig. 6, or moved to position on the rail, as shown in Fig. 5, as the occasion may demand. 85

The pit E is provided with a cover 16 slotted as at 17, and through this slot extends the trip lever 18 which is fulcrumed on the shaft 19 journaled in a bearing 20 fastened to the underside of the cover and directly beneath the rail base. To the inner end of this shaft is attached the lever 21 having connected to the free end thereof as at 22, the forward end of the connecting rod 23. This rod is bent upward so as to extend 95 through the slot 24 and then extends rearward along the inner side of the rail A, the rod being preferably in two sections connected by a turn buckle 25 so that it may be adjusted as to length. The rear end of this connecting rod 23 is bent downward and projected through the slot 26 in the cover 16 of the pit E' and is pivotally connected at 27 to the arm 28 carried at the inner end of the cross shaft 29 which is journaled in 100 bearings at the underside of the cover 16'. The other end of the shaft 29 has fast therewith the segmental arm 30 which is slotted longitudinally at 31. A short vertical rod 32 extends through a slot 33 in the cover 16 and projects at its lower end through the slot 31 in the segmental arm 30, a cross pin 34 passing through the lower end of the rod 32 and prevents the disconnection of the rod from the arm 30, while permitting the rod to have movement in the slot 31. A small roller 35 is carried by the rod 32 and rides upon the upper face of the segmental arm 30 at the sides of the slot. 105

From the description thus far given, it is to be understood that when it is desired to use the apparatus an operator takes two of the skids or blocks and hooks the same to the rod 14 by means of the clips 15 and turns the blocks so that they lie to one side of the rail as shown, for instance, in Fig. 6, and also at the left in Fig. 1. Now, it is to be understood that the blocks are placed properly with relation to the vertical rods 32 and 36, that is to say with the upper ends 110 115 120 125 130

of these vertically moving rods socketed in the grooves 6 of the heads of the skids. Of course, when so positioned, the rail A is unobstructed and the car may travel there-
5 along unimpeded, it being presumed that the braking mechanism of the car is in working condition so that the brakeman may operate the same to bring the car to a stop at a selected point along the track.
10 Should the brakeman, discover, however, that the brakes will not work, and that the car is running away, he signals this fact to the operator in the switch tower and such operator, through the mechanism which we
15 will now proceed to describe, places our apparatus in operative relation with the track to stop the car.

Located in the pit E is a solenoid magnet M adapted to be energized by the act of the operator in the switch tower pressing a button, or closing a switch to complete an electric circuit through the magnet, through suitable conductors (not shown). The plunger 37 of the magnet carries a beveled stem 38 which is normally forced outward by the usual spring of the solenoid so that it engages with a notch 39 in the lower portion of the stem 40. This stem 40 extends through and works in the valve casing 41 which is divided by the cross partition 42 into an upper chamber 43 and a lower chamber 44, the upper end of the stem 40 extending through an opening in the partition 42 as shown in Figs. 9 and 10. An air pipe 45 leads from a suitable source of air supply, such as a compressed air tank to the chamber 43, while 46 indicates an exhaust pipe from the chamber 44. A cylindrical valve 47 is secured to the upper end of the stem 40 and is located within the chamber 43, while the valve disk 48, of greater area than the valve 47, is carried by the stem 40 and is located in the lower chamber 44. A coiled expansion spring 49 is coiled about the stem 40 and is interposed between the valve 48 and the bottom of the valve casing 41, the normal tendency of this spring being to push the stem 40 upward so that the valve 47 will uncover the air inlet pipe 45, while the valve disk 48 will move to a position above and thus close off the exhaust through the pipe 46, as shown in Fig. 9, this taking place when the stem 38 of the solenoid plunger is withdrawn from the notch 39 in the stem 40, as hereinafter described.

The numeral 50 indicates a relatively large air cylinder, the bottom 51 of which has a spider plate 52, the openings 53 of which provide means of communication with the chamber 54 cast integral with and depending from the bottom of the cylinder 50.

The numeral 55 indicates a web or casting extending between the chamber 54 and the valve casing 41, and this web is bored to provide a lateral port 56 extending between

the bottom of the chamber 43, and the upper portion of the chamber 54 and a lateral port 57 extending between the upper portion of the chamber 44 and the lower portion of the chamber 54.

The lower portion of the rod 36 extends into the cylinder 50 and carries at the lower end a piston 58. The portion of the rod 36 within the cylinder is bored to provide the longitudinal socket 59 adapted to slidably receive the stem 60, the upper end of which carries a nut 61, by means of which and the plate 62 the stem is loosely connected with the piston. The plate is slotted at 63 and the piston recessed at 64 to enable the nut to be fitted into the socket 59 in the well known manner. The lower end of the stem 60 which passes through the center of the spider 52, is enlarged in cross diameter and this enlarged section, shown at 65, projects into the chamber 54 and carries at its lower end a semi-cylindrical valve 66 confined by the collars 67. This valve 66 is for the purpose of controlling the air ports 56 and 57. The bottom wall of the chamber 54 is provided with a recess 68 in which the collar at the lower end of the stem may seat.

In the installation of our apparatus the cylinder 50 and its associated parts are disposed in the pit as shown particularly in Figs. 4 and 5 with the rod 36 extending through the top of the pit and into the slot 6 of the head 1 of the skid F. At this time we will assume that the piston 58 in the cylinder 50 is pressed into contact with the bottom of the cylinder by the expansion spring 69 coiled about the stem 36 and bearing at one end against the piston and at its opposite end against the top of the cylinder. The plate 62 on the piston head bears against the enlarged end 65 of the stem 60, and has forced the stem downward so that the valve 66 in the chamber 54 closes the port 57, while the port 56 is open. The stem 38 of the solenoid plunger is holding down the valve stem 40 against the tension of the spring 49 so that the valve 47 closes the air pipe 45 and the valve disk 48 is at the bottom of the valve cylinder, thus opening the exhaust pipe 46. This is the inoperative position of the parts. Now, should the brakeman on the car signal to the operator in the switch tower that the car has gotten beyond the brakeman's control, the operator by actuating a suitable switch or button, closes an electric circuit to the magnet M, energizing the latter so that the plunger is drawn inward, pulling the stem 38 from the notch 39 in the valve stem 40. Immediately, the spring 49 expanding, pushes the stem 40 upward, opening the valve 47 and moving the valve disk 48 to cut off or close the exhaust pipe 46, as shown in Fig. 9. The compressed air now passes from the pipe 45, through the cham-

ber 43, port 56, through the openings 53 in the spider, into the cylinder 50 beneath the piston 58, pushing this piston upward against the tension of the spring 69, thus causing the rod 36 to be moved vertically and thus push or turn the skid F over onto the track A to the position shown in Fig. 2. When the piston 58 reaches a point near the limit of its upward movement the plate 62 contacts with the nut 61, and the stem 60 is pulled upward so that the valve 66 will close the air inlet port 56, thus cutting off the air pressure, and the spring 69 expanding pushes the piston 58 downward, so that the air in the cylinder is forced through the openings 53, chamber 54, port 57 to the chamber 44 and acting on the piston disk 48 depresses the latter against the tension of the relatively light spring 49, thus moving the stem 40 downward and causing the valve 47 to close the air inlet pipe 45 while the valve disk 48 moves downward to open the exhaust pipe 46 so that the air from beneath the piston 58 is exhausted through the pipe 46. At this time the operator in the tower is presumed to have released the switch or push button so that the magnet M is deenergized and the stem 38 again engages the notch 39 in the valve stem 40. When the piston 58 in its descent, strikes against the top of the enlarged lower section 65 of the stem 60, it pushes the valve 68 downward to the position shown in Fig. 9, again opening the port 56 and closing the port 57, and at this time the stem 36 has been lowered to its normal position ready for the next operation.

When the front skid F has been placed upon the track, as shown in Fig. 2, by the operation of the electro-pneumatic device just described, it lies adjacent to the upper end of the lever 18, while the rear skid F' is still inverted and lies to one side of the rail A. As the adjacent front wheel of the front truck strikes the skid F, it rides up on the skid, as shown in the drawings, and pushes or slides the skid along the track so that the lug 13 at the side of the skid strikes the lever 18, moving the latter forward, thus turning the shaft 19, shifting the connecting rod rearward, rocking the shaft 29 in the rear pit E', thus lifting the segmental arm 30 and elevating the vertical rod 32, the upper end of which lies in the slot 6 in the skid F'; so that this skid is turned or lifted onto the track in position to engage the adjacent wheel of the rear truck D', as shown in Fig. 3. The car can, therefore, only travel a short distance, carrying the skids along the track with it, when it will be brought to a stop. It is, of course, to be understood that when it is desired to replace the skid blocks in operative position relative to the remainder of the apparatus, the trainman will detach the blocks, and carry

them back to the pits, and again remount the same on the rod 14. The rear vertical rod 32, and the connections with the lever 18 may be restored to normal position shown in Fig. 2 by the trainman grasping the lever 18 and throwing it back.

While we have herein shown and described one particular embodiment of our invention, we wish it to be understood that we do not confine ourselves to all the precise details of construction herein set forth by way of illustration, as modification and variation may be made without departing from the spirit of the invention or exceeding the scope of the appended claims.

What we claim is:

1. The combination with a skid adapted to slide on a trackway when engaged by the wheel of a car traveling on the rail, a support located alongside the rail, a connection between the support and the skid, whereby said skid may be moved into operative position on top of the rail and into inoperative position alongside the rail, and electro-pneumatic mechanism for moving the skid from inoperative position alongside the rail to operative position on the rail.

2. The combination with a skid block adapted to slide on a track rail when engaged by a wheel of a car traveling on the rail, a support located alongside the rail, a hinge connection between the support and the skid block enabling the latter to be elevated from inoperative position alongside the rail into operative position on top of the rail, and mechanism for elevating the skid block from inoperative to operative position, said mechanism including an electro-pneumatic device located in a pit adjacent the rail and a pusher member normally in contact with the skid block when the latter is in its inoperative position, said pusher member being actuated by the electro-pneumatic device at a desired time to elevate the skid block on the track.

3. The combination with a skid adapted to slide on a trackway when engaged by the wheel of a car traveling on the rail, said skid including a head portion and a beveled tail portion, and a roller housed in the body of the skid and adapted to bear against the top of the rail, a guide rod extending longitudinally of the rail, a clip detachably hinging the skid to the rod to enable the skid to be moved from inoperative position alongside the rail into operative position on top of the rail, a pusher member adapted to engage with the skid to move it from its inoperative to its operative position, and remotely controlled mechanism for actuating the pusher member to move the skid.

4. The combination with a pair of skids adapted to slide on a track rail when engaged by the wheels of a car traveling on the rail, supporting means located alongside

the rail, connections between the skids and the supporting means enabling the skids to be swung from inoperative position alongside the rail into operative position on top of the rail, means for swinging one of said skids into operative position on the rail, and mechanism interposed between the two skids and actuated by the sliding of the skid first moved onto the rail, for swinging the other 10 skid onto the rail.

5. The combination with two skids spaced apart and adapted to slide on a track rail when engaged by the wheels of a car travelling on the rail, supporting means located 15 alongside the rail, hinge connections between the skids and the supporting means enabling the skids to be swung from inoperative position alongside the rail into operative position on top of the rail, independ-

ent means for moving one of said skids from 20 inoperative position into operative position, and mechanism operable upon the sliding of the last mentioned skid for swinging the other skid into operative position on the rail, said mechanism including a trip lever 25 movable by said last mentioned skid, a lifting member engaging with the other skid when the latter is in inoperative position, and power transmitting connections between the lever and the lifting member. 30

In testimony whereof, we affix our signatures in the presence of two witnesses.
